DESIGN FOR A CUTTING SPEED INDICATING DIAL

William F. Groene, Cincinnati, Ohio, assignor to
The R. K. LeBlond Machine Tool Company,
Cincinnati, Ohio, a corporation of Delaware

Application August 29, 1939, Serial No. 86,936

Term of patent 14 years

To all whom it may concern:

Be it known that I, William F. Groene, a citizen of the United States and a resident of Cincinnati, in the county of Hamilton and State of Ohio, have invented a new, original, and ornamental Design for a Cutting Speed Indicating Dial, of which the following is a specification, reference being had to the accompanying drawings, forming part thereof.

Figure I is a front elevation of the cutting speed indicating dial showing my new design.

Figure II is a plan view of the cutting speed indicating dial shown in Figure I.

Figure III is a perspective view of the cutting speed indicating dial shown in Figures I and II.

I claim:

The ornamental design for a cutting speed indicating dial, substantially as shown.

WILLIAM F. GROENE.
